(57) **CLAIM**

The ornamental design for syringe, as shown and described.

DESCRIPTION

FIG. 1 is a perspective view of one embodiment of a syringe showing the new design for a syringe.

FIG. 2 is a right side elevation view thereof;

FIG. 3 is a top plan view thereof;

FIG. 4 is a bottom plan view thereof;

FIG. 5 is a left elevation view thereof;

FIG. 6 is a front elevation view thereof; and

FIG. 7 is a rear elevation view thereof.

FIG. 8 is a perspective view of another embodiment of a syringe showing the new design for a syringe, where a portion of the flange is transparent.

FIG. 9 is a right side elevation view thereof;

FIG. 10 is a top plan view thereof;

FIG. 11 is a bottom plan view thereof;

FIG. 12 is a left side elevation view thereof;

FIG. 13 is a front elevation view thereof; and,

FIG. 14 is a rear elevation view thereof.

The portions of the syringe in FIGS. 1-14 shown in broken lines are included to show features that form no part of the claimed design.

The syringe is shown with a symbolic break in its length. The appearance of any portion of the article between the break lines forms no part of the claims design.

1 Claim, 6 Drawing Sheets
